I. A. BURNETT

DENTAL MANDREL

Filed March 30, 1923

Inventor:
Ira A. Burnett:
By Chas. C. Tillman
Attest

UNITED STATES PATENT OFFICE.

IRA A. BURNETT, OF CHICAGO, ILLINOIS.

DENTAL MANDREL.

Application filed March 20, 1923. Serial No. 228,750.

To all whom it may concern:

Be it known that I, IRA A. BURNETT, a citizen of the United States, residing at Chicago, in the county of Cook and State 5 of Illinois, have invented certain new and useful Improvements in Dental Mandrels, of which the following is a specification.

This invention relates to improvements in dental mandrels, used in connection with 10 dental-engine hand-pieces for numerous purposes, and particularly to that type thereof designed for use in holding paper disks employed in dental operations of various kinds.

15 The principal object of the invention is the provision of a mandrel which will positively hold the paper disks commonly used by dentists, in such a manner as to prevent them becoming loose on the mandrel and 20 ineffective upon the reverse movement of the engine hand-piece, thereby overcoming this annoying difficulty, which all dentists have experienced, and furnishing a mandrel adapted for rotation in either direction without 25 the disk carried thereby becoming loose.

An additional object of the invention is, 30 to provide a mandrel having means whereby a disk can be quickly and tightly secured thereon by the rotation of the mandrel 35 while it is in operative connection with the engine hand-piece, or the removal of the disk can be readily effected while the mandrel is so connected, by the reverse rotation thereof.

The invention contemplates as a further 35 object thereof, the provision of means for so mounting and holding the disk that it can be readily pierced by certain elements of the device without unduly flexing the disk, and so that it will be maintained in 40 the same plane throughout its entire diameter.

The invention will be explained and more readily understood when read in conjunction with the accompanying drawing, which 45 illustrates various embodiments of which the invention is susceptible, it being understood that various other arrangements and modifications may be resorted to without departing from the spirit of the invention, 50 so long as they come within the scope of the appended claims forming a part hereof.

In the drawing,—

Fig. 1 is a greatly enlarged plan view of a paper disk and one of the clamping or gripping members of the mandrel.

Fig. 2 is a vertical sectional view taken

on line 2—2 of Fig. 1 looking in the direction indicated by the arrows.

Fig. 3 is a plan sectional view taken on line 3—3 of Fig. 2.

Fig. 4 is an inner face view of one of the clamping members of the device.

Fig. 5 is a similar view of a modified form of said clamping member, and

Fig. 6 is a view similar to that of Fig. 65 2 and of like parts, but showing a modification in the construction of the pin-carrying member of the device.

Corresponding numerals of reference refer to like parts throughout the different views 70 of the drawing.

Referring now more particularly to Figs. 1 to 4 inclusive of the drawing, the shank of the mandrel is designated by the numeral 10, and as shown, has integral therewith at one of its ends a clamping member 11 which is provided with a plurality of guide openings 12 by preference two of such openings, which are located diametrically opposite each other as more clearly 80 shown in Figs. 2 and 3 of the drawing. A portion of the shank 10 below the clamping member 11 thereon is provided with left-hand screw-threads which terminate at their lower ends at about the longitudinal middle of the shank and at their upper ends a distance below the lower surface of the head 11. The unthreaded portion of the shank 10 is adapted to fit in a suitable socket in an engine hand-piece and to be held therein by 90 a suitable clutch mechanism with which such hand-pieces are provided.

Extended centrally through the member 11 of the shank and longitudinally into the upper portion of the shank is a screw-threaded opening 13 for the reception of a screw 14 extended centrally from the inner face of the other clamping member 15 of the device. The threads of the screw 14 are of the right-hand type, while as before 100 stated, the threads on the exterior of the shank are left-handed ones. The clamping member 15 is provided on its inner or lower surface and centrally thereof with an annular enlargement 16 from the free end of 105 which the screw 14 is extended. The inner or lower surface of the member 15 is provided with an annular flange 17 which as shown is spaced from the enlargement 16 but terminates at its edge in the same plane 110 with the free end of the enlargement 16 of said member. The floor or surface of the

member 15 between the enlargement 16 and the annulus 17 is provided with a plurality of recesses 18 which are located concentrically with respect to the enlargement 16 and flange 17 for the purpose to be presently explained.

In the modified form of the upper or outer clamping member of the device shown in Fig. 5, the structure thereof is the same as that shown in Figs. 2 and 4 and above described, except that instead of employing circular depressions or recesses 18 in the lower surface of the said clamping member, a series of radially disposed grooves 19 are used.

Slidably mounted on the shank 10 just below the clamping member 11 is a collar 20 which has extended therefrom a plurality of dowel pins 21 which are of the same number as the openings 12 in the member 11 and are arranged to slide freely therein. These pins may be secured at their lower ends to the collar 20 in any suitable manner but have their upper or free ends pointed in order to readily pierce the disk 22 to be held by the mandrel.

The pins 21 are so arranged on the collar 20, and the openings 12 in the member 11 are so disposed that the pins 21, when projected as shown in full lines in Fig. 2 of the drawings, will engage a pair of the recesses 18 in the upper or detachable clamping member, thus preventing said member being turned independently of the member 11 or of the disk. The collar 20 is provided with an annular groove 23 in its depending neck 24 for the reception of an inwardly extended annular flange 25 on the upper end of the controlling nut or member 26 which is provided with a centrally and longitudinally extended screw-threaded opening for engagement with the screw-threaded portion of the shank 10 of the device. By this arrangement it is manifest that as the parts are quite small, the flange 25 can be rolled so as to extend into the groove 23 of the neck 24 of the collar 20, thus affording a swivel connection between the collar and the controlling nut or member. At the lower end of its screw-threads, the shank 10 is provided with a stop member 27 which can be fixed on the shank by any suitable means after the collar and controlling member have been placed thereon.

In the modified form shown in Fig. 6, the collar which is swiveled to the upper end of the controlling member or nut 26, as shown in Fig. 2 and above described, is dispensed with, and a coiled spring 28 encircling the pins 21 below the member 11 and resting at one of its ends against said member and at its other end against a plate or collar 29 to which the lower ends of the pins are secured, is employed. This plate 29 is slidably mounted on the shank 10 and

adapted to rest on the upper end of the controlling member or nut 26 by means of which member the plate or collar 29 as well as the pins 21, can be projected towards the detachable gripping member 15 by turning the controlling member 26 in the proper direction to cause such movement.

From the foregoing and by reference to the drawing, it will be readily understood and clearly seen that assuming it is desired to place a disk 22 in operative position on the mandrel, and assuming that the detachable clamping member 15 has been removed from the position shown in Fig. 2 and that the collar 20 and pins 21 carried thereby have been caused to assume the position shown by dotted lines in Fig. 2, it is evident that the free or pointed ends of the pins 21 will be disposed about flush with the upper surface of the clamping member 11, when a disk 22 having a central opening therein, can be placed on the screw 14 of the clamping member 15, when said screw can be inserted into the screw-threaded opening 13 of the member 11 and caused to assume about the position shown in Fig. 2 by turning the clamping member 15 in the proper direction.

Now by advancing the controlling nut or member 26 on the shank 10 from the position shown by dotted lines in Fig. 2, to those shown by continuous lines in said figure, it is apparent that the pins 21 will pierce the disk 22 and engage recesses on the lower or inner surface of the member 15, thus locking the members 11 and 12 on the disk 22 against independent movement. By providing the clamping member 15 with the annular enlargement around the base of its screw 14 and with the annular flange 17, which enlargement and flange terminate at their lower portions in the same plane, it is manifest that the disk will be supported in such a way that the pins 21 can readily pierce the same without materially flexing the disk and thereby distorting its outer or operative portion.

When the parts shall have been positioned as just above explained, it is manifest that the shank of the mandrel can be inserted in an engine hand-piece for use, and it will be understood that the disk 22 will be firmly held on the device whether the engine is operated in its normal or reverse direction. If it should be desired to remove the disk from the mandrel, this can be readily done while the mandrel is in position on the hand-piece by simply applying pressure to the controlling nut or member 26 with the thumb of one hand and causing the shank to be rotated in the proper direction, which will cause the controlling member 26 to be retracted towards the stop member 27, thus withdrawing the pins 21 from the disk and permitting the detachable clamping member

15 to be unscrewed from the member 11 and removed with the disk if desired. As the member or nut 26 is swiveled to the collar 20, it is apparent that by turning the member 26 in the proper direction, said collar and the pins 21 which it carries will be correspondingly advanced or retracted.

In the modified construction shown in Fig. 6, practically the same operation as just above described is employed, except that by the use of the spring 28, the plate or collar 29 carrying the pins 21 is held in contact with the controlling member 26 instead of being swiveled thereto as in the former described construction.

While I have shown in Fig. 2, the slidable collar 20 equipped with two pins 21, and in Fig. 6 the collar or plate 29 equipped with a pair of pins for piercing the disk and for engaging the detachable clamping member, and while I prefer to use a pair of pins in each of the constructions, yet it is obvious that one pin only may be used, without a departure from the spirit of the invention.

Having thus fully described my invention, what I claim as new and desire to secure by Letters Patent is:—

1. A dental mandrel comprising a shank provided at one of its ends with a clamping member having a screw-threaded opening, said shank having a screw-threaded portion on its exterior, another clamping member having a screw to engage said opening and adapted to co-operate with the first named member to clamp a disk between them, a controlling member in screw engagement with the shank, a collar slidably mounted on the shank between the controlling member and the first named clamping member, and at least one pin carried by said collar and

adapted to pierce the disk and to engage the detachable clamping member of the device.

2. In a device of the class described, the combination with a shank having external screw-threads and provided at one of its ends with a clamping member having centrally therein a screw-threaded opening and also having at least one guide opening, of another clamping member having a screw to detachably engage said threaded opening and adapted to co-operate with the first named member to clamp a disk between them, the last named clamping member having on its surface adjacent the first named clamping member an enlargement at the base of its screw and at its periphery a flange terminating substantially in the same plane with said enlargement, means slidably mounted on the shank and having at least one pin operable in a guide opening of the first named clamping member for piercing the disk and engaging the detachable clamping member between its flange and said enlargement, and means on the shank co-operating with said slidable means for advancing and retracting the latter.

3. A clamping member having on its surface adjacent the object to be clamped an annular enlargement provided with a screw extended centrally therefrom and having at its edge a flange spaced from said enlargement and terminating substantially in a plane with the end of the enlargement adjacent the object to be clamped, said member also having the base of the space between its enlargement and flanges recessed and adapted for engagement with a projection inserted into said spaces.

IR A. BURNETT.
